Specification for Design.

Patented Dec. 21, 1915.

Application filed May 12, 1915. Serial No. 27,711. Term of patent 14 years.

To all whom it may concern:

Be it known that I, **HARRY B. GREENE**, a citizen of the United States, residing in Hasbrouck Heights, Bergen county, and State of New Jersey, have invented a new, original, and ornamental Design for Cabinets for Phonographs, of which the following is a specification, reference being had to the accompanying drawing, forming part thereof.

The figure is a perspective view of a cabinet for phonographs illustrating my new design.

I claim:

The ornamental design for a cabinet for a phonograph substantially as shown.

In testimony whereof I have hereunto signed this specification.

HARRY B. GREENE.
